(57) **CLAIM**

The ornamental design for an electrical socket with cover, as shown and described.

DESCRIPTION

FIG. 1 is a top, side perspective view of an electrical socket with cover, showing my new design;

FIG. 2 is a bottom, side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings are included for the purpose of illustrating portions of the electrical socket with cover that form no part of the claimed design.

1 Claim, 8 Drawing Sheets
